UNITED STATES PATENT OFFICE.

WILLIAM H. FURNESS, OF NATIONAL PARK, FRITZ HEIDLBERG, OF JERSEY CITY, AND
CHARLES E. VANDERKLEED, OF COLLINGSWOOD, NEW JERSEY.

METHOD OF OPERATING INTERNAL-COMBUSTION ENGINES.

1,287,282.

Specification of Letters Patent. Patented Dec. 10, 1918.

No Drawing.

Application filed May 13, 1916. Serial No. 97,371.

To all whom it may concern:

Be it known that we, WILLIAM H. FURNESS, FRITZ HEIDLBERG, and CHARLES E. VANDERKLEED, residents of National Park, Gloucester county, New Jersey; Jersey City, Hudson county, New Jersey, and Collingswood, Camden county, New Jersey, respectively, we, the said FURNESS and VANDERKLEED, being citizens of the United States, and I, the said HEIDLBERG, being a subject of the Emperor of Austria, have invented certain Methods of Operating Internal-Combustion Engines, of which the following is a specification.

One object of our invention is to provide a method of utilizing certain of the heat now wasted or lost in the operation of internal combustion engines, with a view to materially increasing the power secured from the combustion of a given quantity of fuel.

It is further desired to provide a method of the nature above indicated which shall permit of the operation of internal combustion engines at such a low temperature as will obviate the necessity for the water or air cooling systems commonly used and which shall increase the efficiency of the engine by reducing the thermal gradient between the heated gases and the cylinder walls.

In carrying out our invention we inject or otherwise admit to the engine cylinder or cylinders, with or preferably independently of the fuel a sufficient amount of a compound such as ammonium carbonate, urea, ammonium carbamate, etc., which at a high temperature is dissociated into its constituent gases, absorbing heat from the combustion of the charge, and lowering the initial pressure resulting from the explosion or combustion of the fuel but maintaining a higher average pressure throughout the greater part of the piston stroke. The two principal constituents of ammonium carbonate, which is the material we preferably employ, are permanent gases at all temperatures and pressures within the range of the greater part of the working stroke of internal combustion engines, as is also the steam formed by the vaporization of the water. These gases occupy many times the space taken by the small quantity of solution introduced into the cylinders, and aid in the propulsion of the piston, con-

tinuing to act expansively until the exhaust is opened. The amount of ammonium carbonate injected or admitted is so regulated that the power produced is a maximum with a given fuel consumption, it appearing that this condition is fulfilled when the pressure in the cylinder remains at such a point and the temperature falls sufficiently near the end of the working stroke, that there is a recombination of carbon dioxid and ammonia with a reformation and precipitation of ammonium carbonate within said cylinder before the opening of the exhaust port. Such opening liberates the nitrogen, excess carbon dioxid and steam, permitting the injection of a new charge of air and combustible material.

Since the gases formed by the compound introduced, in expanding absorb heat, not only from the products of combustion but from the walls of the cylinder and the piston, these latter may be maintained by such gases at a low temperature not requiring the air or water cooling systems commonly used, and owing to this possibility there is little if any interference with the proper lubrication of the various parts.

It is conceivable that compounds other than ammonium carbonate such as urea, ammonium carbamate, etc., may have the same beneficial effect as that above indicated, when decomposed into their constituent gases in the cylinder of an internal combustion engine at the proper time, and in the presence of suitable amounts of combustion products and air, and it is to be understood that the use of these would properly fall within the scope of my invention. Commercial ammonium carbonate, however, appears to be especially suited for this use, since it is easily introduced in suitable quantities, which depend of course upon the dimensions of the engine and to some extent also upon the nature and quantity of the fuel used. Moreover it decomposes into gases without leaving any solid residue and these gases are permanent at the pressures and temperatures to which they are exposed during the greater part of the working stroke of the engine.

For purposes of our invention it is immaterial what fuel is employed, since in any case it is impossible under working conditions for such fuel or the products of its combustion, to combine with the two inert gases formed by the decomposition

- of the ammonia compound. We have found, however, that in a small two cycle gasoline marine engine the introduction of several ounces of a saturated solution of ammonium carbonate in water, before starting and the subsequent admission at each stroke of small additional amounts of the same solution, not only added materially to the power of the engine but permitted it to be run indefinitely 5 at a temperature which did not require the operation of the water cooling system. We have found advantageous results also to accompany the feeding of ammonium carbonate into the cylinders of an automobile 10 engine at the rate of from ten to twenty-five drops per minute of a saturated solution of the carbonate and methyl alcohol. In our experience however superior results are attained by the use of an aqueous solution of 15 ammonium carbonate, possibly in view of the fact that the water is not combustible. It is likewise immaterial whether the engine is of the reciprocating or of the rotary type, since in any case the invention 20 contemplates the use of ammonium carbonate or equivalent decomposable though non-combustible material, the effect of which is to exert a high pressure at low temperature, and which does not materially 25 decrease during expansion, by this means converting the explosive effect of the combustion of the charge into a propulsive effect more nearly related to that of steam in a steam engine. 30 It is to be noted that for all purposes of our invention it is immaterial whether the decomposition of the ammonium carbonate or other substance introduced, is due to the heat of the piston or other structure upon 35 which it is delivered, or is caused by the heat developed by the combustion of a fuel charge simultaneously with or immediately after its admission to the cylinder. Obvi-

ously the gas producing compound may be introduced at other times instead of immediately before the ignition of the fuel charge, for by the use of suitable means it can be introduced at the time of the explosion or even after the same if it should be considered advisable. 45

So far as we have been able to determine, the function of the substance added to the fuel is that of a retarder of combustion which permits of the gradual and relatively more efficient action of the products of combustion. While water may be used as a vehicle or solvent for the substance to be decomposed, it is to be understood that other substances such as methyl alcohol or similar solvents may be used without departing 50 from our invention. 55

If desired or found advisable, we may recover from the exhaust of the engine the ammonia gas, using for this purpose any of the well known devices and methods. 60

We claim;—

1. The method of operating an internal combustion engine which consists in supplying thereto a combustible charge and ammonium carbonate; and igniting the charge and 70 substantially simultaneously decomposing the ammonium carbonate into its gaseous constituents to produce a body of gases for actuating the moving element of the engine. 75

2. The method of operating an internal 80 combustion engine which consists in supplying thereto a charge of fuel and a relatively small quantity of a solution of ammonium carbonate; igniting the fuel and decomposing the ammonium carbonate to produce a body of gases for actuating the moving element of the engine; and exhausting the expanded gases. 85
